UNITED STATES PATENT OFFICE.

CHARLES PROMISLO, OF PHILADELPHIA, PENNSYLVANIA.

CLIP FOR CARTON LIDS.

Application filed June 17, 1922. Serial No. 568,953.

To all whom it may concern:

Be it known that I, CHARLES PROMISLO, a citizen of the United States, residing at Philadelphia, in the county of Philadelphia and State of Pennsylvania, have invented 5 certain new and useful Improvements in Clips for Carton Lids, of which the following is a specification.

My invention relates to a clip or holder 10 for carton or box lids and is especially designed for the purpose of holding the lid or top flap of a carton in an open or raised position at any desired angle to exhibit the price information and advertising data 15 thereon, and the brand and trade-mark of the goods contained in the carton, such as candy confections.

These objects, and other advantageous ends which will be described hereinafter, I 20 attain in the following manner, reference being had to the accompanying drawing in which—

Figure 1 is a perspective view of the device in applied position,

25 Figure 2 is a plan view,

Figure 3 is a front elevation, and

Figure 4 is a side elevation.

Referring to the drawing in detail, 5 represents a carton or box adapted to contain 30 the goods to be displayed and sold, and 6 is the lid or top flap upon which the advertising data and price information appear. The holder or clip generally designated at 7, consists of a section of wire or 35 other resilient material bent to form coils 8 and 9, the coil 9 being off-set from the coil 8, that is, made smaller in diameter so that coil 9 will extend below coil 8 as indicated at 10, and facilitate the application 40 of the gripping device to the upper edge of a side of the carton adjacent to the flap 6 as indicated in Figure 1 of the drawings. These coils have their top portions substantially in contact as indicated at 11 and di- 45 verge downwardly to frictionally grip the side of the box or carton.

The end 12 of the wire should extend toward the rear of the carton and be blunt to prevent injury to the hand, the carton or

the contents of the carton, or from piercing 50 the side of the carton when the device is applied. From the coil 9, the wire is off-set laterally as indicated at 13 and then bent in a substantially opposite direction over the coils 9 and 10 as indicated at 14, to form 55 an arm 15 and has a substantially horizontally disposed hook or open loop 16, the free end of which slants slightly forward to form a contracted throat or entrance portion 17 with the outwardly bent portion 18 60 at the juncture of the hook 16 with the arm 7, which receives and firmly holds the lid 6. The arm 15 is arranged to normally spring inwardly and grip the edge of the lid 6 of the box or carton and the end portion 65 of the wire projects to form a bill 19 which serves to guide the lid into the upper gripping member. In view of the angular disposition of the gripping member thus formed at the upper end of the arm 8, the 70 material will be slightly bent or distorted so that the release of the holder will be prevented.

While I have described my invention as taking a particular form, it will be understood that the various parts of my invention may be changed without departing from the spirit thereof, and hence I do not limit myself to the precise construction set forth, but consider that I am at liberty to make 80 such changes and alterations as fairly come within the scope of the appended claims.

Having thus described my invention, what I claim as new and desire to secure by Letters Patent is:—

1. A holder for box lids consisting of a lower gripping member and an upper gripping member, and an arm connecting said gripping members, said arm being off-set outwardly from a plane passing between 90 the jaws of the lower gripping member and then angularly bent and off-set inwardly to the upper gripping member.

2. A clip for carton lids consisting of a section of resilient material bent to form 95 coils disposed in divergent relation, one of the coils extending below the other, the material being bent outwardly and inwardly

to form an inclined resilient arm, the free end of the arm being bent outwardly and inwardly to form a slanting hook having a contracted entrance portion and a projecting bill.

3. A clip for carton lids comprising lower gripping coils; a U-shaped upper gripping member, having a restricted throat and an inwardly projecting bill at the back, and

a connecting member between the gripping coils and gripping member.

In testimony whereof I have signed my name to this specification in the presence of two subscribing witnesses.

CHARLES PROMISLO.
